Mac Buxbaum and Moe Lebensonfeld,
Flushing, N. Y.

Application March 5, 1947, Serial No. 137,382

Term of patent 3½ years

(Cl. D33—19)

To all whom it may concern:

Be it known that we, Mac Buxbaum and Moe Lebensonfeld, both citizens of the United States, both residing at Flushing, New York, in the county of Queens and State of New York, have invented a new, original, and ornamental Design for a Console Bar With Aquarium, of which the following is a specification, reference being had to the accompanying drawing, forming a part thereof.

In the drawing:

Fig. 1 is a perspective view of a console bar with aquarium, showing our new design;

Fig. 2 is a front elevational view;

Fig. 3 is a side elevational view; and

Fig. 4 is a top plan view of the same.

We claim:

The ornamental design for a console bar with aquarium, as shown.

MAC BUXBAUM,
MOE LEBENSFELD.
